ATTACHMENT FOR VIBRATORY SCREENS

Fred K. Betts III, Harrisonburg, Va.

Application September 20, 1949, Serial No. 116,827

1 Claim. (Cl. 209—405)

1

This invention relates in general to screening mechanisms, and more particularly to an attachment for a vibratory screen employing a plurality of removable graduated screens for grading or sifting granular or pulverant material.

As the screens in vibratory screening mechanisms for grading granular material are subject to particularly harsh use in grading the granular material and frequently require replacement or repair, and as it is frequently necessary to change the sizes of wire mesh screen in accordance with the grading desired, from a practical point of view it is important that the individual screens be readily removable from the outer screen housing frame. Conventionally, the screens are provided with framing members which are removably secured to the side walls of the outer screen housing frame, generally by mounting bolts extending through the screen members and through corresponding apertures in the side wall of the screen housing frame, or by pivotal supports retaining the screen frames against supporting ledges or lugs extending inwardly from the sides of the housing or against the sides of the housing frame, the pivotal clamping members having bolts extending through the side walls adapted to be secured outwardly of the screen housing frame by means of lock nuts or the like. These bolts must generally be spaced not more than six inches apart longitudinally of the screens because of the severe strain to which the screens are subjected during vibration. It will be apparent, therefore, that such screen mounting devices involve considerable losses in time and labor in removing and replacing the individual screens within the housing frame, as each of the bolts must be individually uncoupled from its lock nut and withdrawn from the openings in the side wall and from the screen framing members to permit removal of the screens from the housing frame.

It is, therefore, an object of the present invention to provide a novel means for removably mounting sizing screens in a vibratory screen housing, adapted to obviate the above-mentioned disadvantages.

Another object of the present invention is the provision of novel mounting elements for removably securing a plurality of vibratory screens within a vibratory screen housing, of relatively simple and inexpensive construction, which is highly durable and sufficiently strong to permit a high degree of tensioning of metal framed sizing screens.

Another object of the present invention is the

provision of novel means for removably mounting a plurality of sizing screens within a vibratory screen housing, which means are readily adaptable to release the vibratory screens by manipulation of means disposed externally of the screen housing to permit withdrawal of the screens from the housing.

Another object of the present invention is the provision of novel keeper means for releasably securing angle iron framing members of sizing screens relative to the sides of the sizing screen housings, wherein the keeper means are readily operable from externally of the screen housing, which facilitate a high degree of tensioning of the sizing screens when moved into clamping position, and which are operative to draw a flange of the framing members of the sizing screen flush against the side wall of the housing.

Other objects, advantages, capabilities of the present invention will become apparent from the following detailed description taken in conjunction with the accompanying drawings, in which only a preferred embodiment of the invention is shown.

25 In the drawings:

Figure 1 is a side elevation of a vibratory screening mechanism for grading or sifting granular or pulverant material, embodying the present invention, only a portion of the stationary supporting frame and feeding and discharge chutes being shown;

Figure 2 is a top plan view of the vibratory screening mechanism shown in Figure 1;

Figure 3 is a partial vertical sectional view of the lower or discharge end of the grading screen and a portion of the housing frame, taken along the lines 3—3 of Figure 2;

Figure 4 is a vertical transverse section through the vibratory screening mechanism, taken along the lines 4—4 of Figure 1; and

Figure 5 is a vertical section of the clamping means and a grading screen, illustrating the cooperative association of the members to effect clamping of the sizing screen within the housing, taken along the lines 5—5 of Figure 2.

Referring to the drawings, in which like reference characters designate corresponding parts throughout the several figures, the reference character 10 designates a stationary support formed of suitable material such as angle iron members or the like, having two horizontal, laterally spaced rail elements 11 upon which the vibratory screening device is mounted. Between the horizontal spaced rails 11 of the support 10 is disposed a vibratory screen housing frame,

generally indicated at 12, of substantially rectangular horizontal cross section adapted to house a plurality of vertically spaced grading screens 13, 14 and 15 of wire mesh fabric. The rectangular screen housing frame 12 is open along the top and bottom thereof and has side walls 16, 16', a feed end wall 17 having transverse slots 17' therein adapted to permit ingress and egress of the wire mesh screens 13, 14 and 15, and a discharge end wall 18 having transverse discharge openings 19 therein, the bottom of each of the openings 19 being flush with the wire mesh screens to permit discharge of granular material retained thereby by gravitational forces.

A feed chute 20 disposed above the open top of the housing frame 12 is provided to couple the granular substance into the housing frame 12, and extends to a suitable hopper or the like (not shown) for retaining the mixed granular material. Likewise, discharge chutes 21 are coupled to each of the discharge openings 19 in the discharge end wall 18 to couple the graded granular materials retained by each of the screens 13, 14 and 15 into suitable containers (not shown). A bottom discharge chute 22 is likewise provided for coupling the finest grades of granular material passed by each of the grading screens 13, 14 and 15 into another suitable container disposed below the device.

Each of the screens 13, 14 and 15 are of progressively increasing mesh so that the larger granular material will be retained by the upper screens, as 13 and 14, and discharged into their appropriate containers, while the finer granular substances will be passed through to subsequent grading screens, such as screen 15, or through all of the grading screens into the fine granular substance discharge chute 22. The mesh of wire screens, as generally used in the art, is understood to refer to the number of openings per linear inch of screen.

To improve the efficiency of operation of the grading device, it is desirable that the entire grading screen housing frame be vibrated at a relatively high frequency, to effect rapid passage of the granular material through the various grading screens. To permit the grading screen housing frame to be so vibrated, the housing 12 is intercoupled to the rails 11 of the support 10 by means of resilient support bearings, such as the bearings 25, of conventional construction, such as for example metallic drums 26 fixedly mounted to the rails 11, surrounding annular rubber blocks 27 in which metallic lugs 28 bolted to the sides 16 of the housing 12 are disposed. In this manner a considerable amount of oscillatory rocking or vibratory action can be imparted to the screen housing 12. Preferably there are four of these resilient supporting bearings arranged in pairs on each side of the housing 12.

Any suitable form of vibrating mechanism may be used to vibrate the housing member 12 and the screens 13, 14 and 15. Preferably, however, the conventional unbalanced shaft type of vibrating mechanism is employed, comprising an unbalanced or eccentric shaft 30 journaled in bearings 31 on the side walls 16, 16' of the housing 12, extending through bearings 32 fixedly mounted on the horizontal spaced rails 11 of the support 10, and having a pulley 33 keyed to one end of the shaft 30. The pulley 33 may be intercoupled by means of belt 34 to a drive pulley 35 on the shaft of a suitable electric motor 36 of any commercially available type, mounted on a supporting bracket 37 on the fixed support 10.

It will be apparent that continuous rotation of the electric motor drive shaft and drive pulley 35 will rotate the unbalanced eccentric shaft 30 to impart continuous high frequency vibratory motion to the screen housing frame 12 and screens 13, 14 and 15 supported on the resilient bearings 25.

The grading screens 13, 14 and 15 are rectangular in cross section and are disposed on edge supporting shoulder brackets 40 mounted on the inner surfaces of the side walls 16, 16' and feed end wall 17, which are constructed preferably of angle iron bars, the edge supporting brackets 40 on the side walls 16, 16' of the housing 12 being disposed in planes descending from the feed end wall 17 to the discharge end wall 18 and forming an angle of approximately fifteen to eighteen degrees with the horizontal. The grading screens 13, 14 and 15 are constructed of conventional wire mesh fabric, stretched between a substantially rectangular screen frame 41, the side frame members 42, 42' and the end frame member 43 disposed at the feeding end of the housing 12 being constructed of angle iron bars, and the lower discharge end frame member 44 being constructed of a flat metallic strap. The edges of the wire mesh fabric may be rigidly clamped to the lateral flanges of the frame members 41 by means of suitable lengths of flat metallic straps 45 retained against the lateral flange of the frame members 42, 42', 43 and 44 by means of bolts and nuts 46 extending therethrough for clamping the wire mesh fabric between the adjacent surfaces.

Means are provided extending through apertures in the sides 16, 16' of the housing frame 12 which may be operated from externally of the housing to clamp a surface of the angle iron frame members 42, 42' and 43 against the adjacent sides of the housing frame and tension the grading screen laterally. These clamping means comprise right angular keeper elements 50 having an arm 51 adapted to extend through suitable slots 52 in the side walls 16, 16' of the housing 12, and a downwardly depending locking flange 53 adapted to abut against the inwardly disposed face of the upright flanges on the angle iron frame members 42 and 42'. The slots 52 and side walls 16, 16' of the housing 12 are disposed with their lower edges approximately aligned horizontally with the uppermost point on the upright flanges of the angle iron frame members 42, 42'. Suitable struck edges or lugs 54, or other like flared portions, are provided at the outer ends of the arms 51 of the keeper elements 50 formed by peening or the like to prevent the keeper elements 50 from being withdrawn into the inside of the housing 12 through the slots 52. Vertical slots 55 are provided in the keepers 50, extending through the arm 51, adapted to receive wedge-shaped locking members 56 therethrough.

The wedge members 56 taper upwardly to an apex indicated at 56', and are adapted to be inserted in the slots 55 and driven upwardly until the inwardly disposed face 57 of the wedge 56 abuts against the outer face of the side wall 16 or 16', the outer inclined surface 58 of the wedge 56 abutting against the rear edge of the slot 55 to cam the bracket 50 outwardly through the slot 52 and urge the upstanding flanges of the angle iron frame members 42, 42' engaged by the locking flange 53 of the keeper 50 toward the adjacent side walls 16, 16' of the housing 12. If the side wall 16, 16' of the housing 12 is relatively thin,

a suitable apertured spacing block 59 may be disposed over the arm 51 of the keeper 50 and the inner surface 57 of the wedge 56 disposed against the washer 59. Suitable apertures 60 are formed in the wedge 56 spaced longitudinally thereof to permit a retaining pin to be inserted therethrough when the wedge is driven through the aperture 55 to lock the bracket and grading screen in place.

It will be apparent that the removable screen clamping means may be readily adjusted to clamping or releasing condition from externally of the grading screen housing 12 in a very simple manner. The right angle keeper elements 50 are formed of substantial width and thickness so that only four or five of the elements spaced twelve to eighteen inches apart are necessary for effective clamping of the grading screens.

In operation, the keeper elements are pushed inwardly of the side walls 16, 16' until the retaining lugs 54 engage the apertures 52 in the side walls of the housing 12, and the grading screen, such as screen 13, is inserted into the housing 12 through the transverse slots 17 in the feed end wall 17 until the grading screen is wholly disposed within the housing with the frame members 42, 42' and 43 supported on the edge supporting brackets 40. As the discharge end frame member 44 of the grading screen frame 41, which is disposed in the direction of insertion of the screen into the housing 12, is only a flat metal strap 44, the upright flanges of the angle iron screen frame members 42, 42' will slide between the inwardly disposed face of the locking flange 53 on each of the keeper elements 50 and the adjacent inner surface of the side walls 16, 16' of the screen housing. The ends of the arms 51 of the keeper elements 50 are then withdrawn through the apertures 52 in the side walls 16, 16' and the apices 56' of the wedges 56 inserted in the slots 55 of the elements 50. The wedges are then driven upwardly within the slots as far as possible, the inner surface 57 of the wedge bearing against the outer surface of the side walls 16, 16' and the inclined surface 58 of the wedge engaging the rear of the slot 55 to cam the keeper 50 outwardly of the housing 12 and draw the screen frames 42, 42' toward their adjacent side walls 16, 16'.

It will be noted that the forces on the keeper elements 50, apparent from inspection of Figure 5, resulting from the camming action of the wedges 56 in slots 55, likewise tend to cant the angular keeper element in a clockwise direction as viewed in Figure 5, to dispose the lateral and upright flanges of the right angle frame members 42, 42' against the adjacent faces of the edge supporting brackets 40 and side walls 16, 16', respectively. An extremely secure clamping of the frame members 41 of the grading screen is thus obtained, in which both flanges of the angle iron frame members are rigidly clamped against corresponding faces of supporting members, and the side frame members 42, 42' spread outwardly laterally of the housing 12 to effect a high degree of tensioning of the grading screens.

To remove any one of the grading screens 13, 14 and 15 from the screen housing 12 for repair or replacement purposes, the operator need only withdraw the wedge 56 from its slot 55 in the horizontal arms of the keeper elements 50 and push the elements inwardly of the housing side walls 16, 16' as far as they will go to effect withdrawal of the grading screen from the housing. It will be apparent that a considerable saving in time and labor is thus effected in removing and

replacing the grading screens in the above recited manner, as removal of nuts and bolts or the like from the side walls of the housing and the framing members of the grading screens is no longer necessary. Likewise, no means for access to the inside of the screen housing 12 need be provided, as the keeper elements 50 are never entirely withdrawn from the associated side wall apertures 52.

It will be apparent that a novel vibratory screening mechanism and clamping means, therefore, have been provided, in which removal of the individual grading screens is greatly facilitated, as the clamping and unclamping of the grading screens within the screen housing is effected entirely from without the housing. Likewise, a simple, inexpensive, and highly durable construction is provided, in which fewer clamping devices are necessitated for the grading screens, and by which the screens may be tensioned laterally and positively clamped against right angularly disposed supporting surfaces within the screen housing.

While but one specific embodiment of the invention has been particularly shown and described, it is distinctly understood that the invention is not limited thereto, but that various modifications may be made in the invention without departing from the spirit and scope thereof, and it is desired, therefore, that only such limitations shall be placed thereon as are imposed by the prior art and are set forth in the appended claims.

What is claimed is:

A vibratory screening mechanism for grading granular materials and the like comprising a housing having opposed vertical side walls and a screening unit, means on said side walls forming supporting ledges for said screening unit at opposite sides of said housing and projecting inwardly at right angles from said side walls, said screening unit comprising a screening medium bounded by angle irons having transverse flanges connected to said screening medium adapted to seat on said ledges and upright flanges for engaging the side walls of said housing, clamping means intercoupled with said housing for drawing said angle irons against said side walls and thereby stretching and securing said screening medium, said clamping means comprising a plurality of rigid hooks located in spaced relation longitudinally along each of said side walls, said hooks each being formed of bars of substantially rectangular cross section bent into right angular shape along a transverse axis substantially midway of its length to define an arm extending through the side walls of said housing in substantially perpendicular relation thereto and a depending finger extending at right angles to said arm and parallel to said side walls in overlying and engaging relation with the upright flanges of said angle irons to draw the upright flanges of said angle irons against the side walls of said housing, each of said arms having a vertical slot extending therethrough, and upwardly converging wedge-shaped members disposed externally of said housing and extending through said slots, said wedge-shaped members bearing against said housing side walls for camming said hooks outwardly of said housing and canting the depending fingers of said hooks downwardly to lock the upright flanges of said angle irons in intimately contacting relation throughout with said housing side walls and said transverse flanges in intimately con-

taeting relation throughout with said supporting ledges.
